UNITED STATES PATENT OFFICE.

WENZEL J. DVORAK, OF HOUSTON, TEXAS.

WALL CONSTRUCTION.

Application filed June 30, 1922. Serial No. 571,888.

To all whom it may concern:

Be it known that I, WENZEL J. DVORAK, citizen of Czechoslovakia, residing at Houston, in the county of Harris and State 5 of Texas, have invented certain new and useful Improvements in Wall Construction, of which the following is a specification.

This invention relates to new and useful improvements in a wall construction.

10 One object of the invention is to provide a concrete wall formed of novelly constructed wall slabs, anchored together in a wall structure in the novel manner hereinafter described.

15 With the above and other objects in view the invention has particular relation to certain novel features of construction, arrangement of parts and use, an example of which is given in this specification and illustrated 20 in the accompanying drawings, wherein:—

Figure 1 is an elevation of a section of the wall shown partly in section.

Figure 2 is a side elevation of one of the wall slabs shown partially in section.

25 Figure 3 is a longitudinal sectional view thereof.

Figure 4 is a cross sectional view and,

Figure 5 shows an end view of a section of the wall.

30 In the drawings the numeral 1 designates a wall slab which is formed of concreting material. This slab may be of any desired dimensions, but is usually of a length sufficient to reach from the floor to the ceiling 35 of the room being constructed, and is of the width and thickness to give sufficient strength, and be easily handled in erection. This slab has a plurality of reinforcing rods extending from the lower end thereof

40 throughout the length of the slab and projecting a distance beyond the upper end thereof. These reinforcing rods are arranged in pairs as 2 and are wrapped at their upper and lower ends with suitable 45 wires as 3, and intermediate their ends are anchored together by the ties 4. These rods are anchored together as shown and embedded in the material of the slab while it is in plastic state. The margins of the 50 slabs have lengthwise grooves, the grooves of adjacent edges of adjoining slabs coinciding and forming the key ways 5 from top to bottom of the wall. During the process of erection these key ways are filled with

55 plastic material, which, when it hardens key the slabs together and hold them in

alignment on opposite sides of the upwardly projecting ends of the reinforcing rods 2 are the tie rods 6, 6 which are tied to said ends by suitable ties as 7. These are provided so that when the overhead beam above the wall is poured in place it will harden around said upwardly projecting ends of said tie rods 6 forming a secure anchorage for the upper ends of the slabs. At suitable places wooden blocks as 8 are embedded within the slabs to which picture molding and the like may be anchored. The slabs adjacent door and window openings have bolts as 9 embedded therein whose outwardly projecting ends are threaded to receive the nuts 10, said bolts projecting through the facing 11 of the opening and the nuts securing said facing in place.

What I claim is:—

1. A wall constructed of slabs formed of a concreting material, the adjacent edges of adjoining slabs having coinciding lengthwise grooves, lengthwise rods embedded in and extending lengthwise with respect to the slabs and projecting beyond the upper ends of said slabs, wires wrapped around said rods at their respective ends and embedded in said slabs.

2. A wall constructed of slabs formed of a concreting material, the adjacent edges of adjoining slabs having coinciding lengthwise grooves, lengthwise rods embedded in and extending lengthwise with respect to the slabs and projecting beyond the upper ends of said slabs, wires within the slab and wrapped around the respective ends of the rods and tie rods secured to said projecting ends.

3. A wall construction of slabs formed of a concreting material, the adjacent edges of adjoining slabs having coinciding lengthwise grooves, lengthwise rods embedded in and extending lengthwise with respect to the slabs and projecting beyond the upper ends of said slabs, wires wrapped around said rods at their respective ends and embedded in said slabs, and ties anchoring said rods together intermediate their ends.

In testimony whereof I have signed my name to this specification in the presence of two subscribing witnesses.

WENZEL J. DVORAK.
